(57) **CLAIM**

The ornamental design for a barrier opener head, as shown and described.

DESCRIPTION

FIG. 1 is a perspective view of a first embodiment of a barrier opener head showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines defining the large rectangle in the center of the barrier opener head as shown in FIG. 2, and also seen in FIGS. 1 and 6 as well as the broken lines defining the large rectangle to the right and above the center of the barrier opener head as shown in FIG. 7 represent the bounds of the claimed design while all other broken lines are directed to environment and are for illustrative purposes only; the broken lines form no part of the claimed design.
